UNITED STATES PATENT OFFICE.

GEORGE C. BREIDERT, OF CHICAGO, ILLINOIS.

CAR-VENTILATOR.

No. 923,241.

Specification of Letters Patent.

Patented June 1, 1909.

Application filed February 11, 1909. Serial No. 477,400.

To all whom it may concern:

Be it known that I, GEORGE C. BREIDERT, a citizen of the United States, residing at Chicago, in the county of Cook and State of Illinois, have invented a new and useful Improvement in Car-Ventilators, of which the following is a specification.

My invention relates to an improvement in the class of ventilators used on the side-walls of the clear-story or upper deck of a railway-car to cause its motion, by the construction of the ventilator, to force air-currents lengthwise through the latter and thereby exert a suction-action in the ventilator to withdraw through it vitiated air out of the car.

The object of my invention is to provide an improved construction of ventilator, of the type referred to, to the end of rendering it more effective in its purpose.

In the accompanying drawing, Figure 1 is a broken perspective view of a railway-car equipped with ventilators of my improved construction, and Fig. 2 is an enlarged section on line 2, Fig. 1.

The hood 3, which is preferably formed of sheet-metal and of the shape illustrated, comprises an outwardly curved, longitudinally arc-shaped crown 4 with a flat upper side 5 and an externally concave lower side or base 15 to adapt it to conform to the shape of the part of the car-roof upon which it seats. The hood is of general U-shape in cross-section, being open at its ends and having an open face at which it covers the sash-opening in the side-wall of the clear-story C of a car C upon which the ventilator is used. Series of baffle-plates 6 extend inclinedly into the hood from its opposite ends to form between the members of each series inclined air-passages 7, in any desired number, depending on the number of baffle-plates employed which is according to the length of the ventilator. These plates reach from side to side across the ventilator, being either rigidly fastened in place, or not if it be desired to have them adjustable. As shown, three of the baffle-plates are employed in each series and those of each series incline correspondingly, or approximately so, but in contrary direction to those of the other series, whereby the longer innermost plates form between them a V-shaped air-passage 8, open at its apex, and the shorter intermediate plates and the still shorter end-plates, which may be slightly curved, as represented, form the

passages 7. At each end of the hood are provided to extend between its sides and for a short distance into it two similar air-current deflecting plates 9 and 10 correspondingly inclining inwardly toward the crown 4 and forming spaces between them.

With my ventilator fastened in any suitable manner in place on a car, its motion in either direction, as that indicated by the arrow 11 in Fig. 1, will force air-currents lengthwise through it, as in the direction of the arrow 12. These air-currents pass through the hood across the inner ends of the baffle-plates 6 and act to draw the impure air out of the car through the spaces 7, the relation to each other of the plates preventing the fresh air from blowing into the car through the spaces, and this baffling function being enhanced by the curvature of the outer plates. The purpose of the plates 9, 10, of which one or more may be provided in each end of the hood, is to so deflect the wind, when blowing in a direction to strike such plates at or approximately at a right-angle to them, to deflect the air-currents in a manner to direct them straightway through the hood, as indicated by the arrows 13 in Fig. 2, and thus cause them to exert the suction-action described and prevent them from entering the car through the spaces 7.

It will be observed that all of the air-passage-forming baffle-plates 6 extend inwardly from the open face of the ventilator. This is an important feature of my improvement, inasmuch as it enables the number of these plates, in each series thereof, to be varied for ventilators of different lengths. Ventilators of the present class are required, for use in different situations, as in large railway-cars and relatively smaller street-cars, to be of different lengths and of varying capacity, the number of sizes commonly provided being 24-inch, 30-inch, and 48-inch. The device herein illustrated represents the 30-inch size, requiring three baffle-plates for each series thereof, while the 24-inch size requires two and the 48-inch size four of such plates in each series.

What I claim as new and desire to secure by Letters Patent is—

1. A car-ventilator comprising, in combination, a hood with open ends and face, a series of plates extending from one end of the hood between its sides and from its open face inclinedly in one direction toward the crown,

and a similar series of plates extending from the opposite end of the hood like said first-named series but with its members inclining in the opposite direction, said plates forming 5 between them inclined air-passages and between their inner ends and the hood an air-passage lengthwise through the device, for the purpose set forth.

2. A car-ventilator comprising, in combination, a hood with open ends and face, a 10 series of plates extending from one end of the hood between its sides and from its open face inclinedly in one direction, said plates increasing in length in the inward direction of 15 the series, and a similar series of plates extending from the opposite end of the hood like said first-named series but with its members inclining in the opposite direction, said plates forming between them inclined air- 20 passages and between their inner ends and the hood an air-passage lengthwise through the device, for the purpose set forth.

3. A car-ventilator comprising, in combination, a hood with open ends and face, a 25 series of plates extending from one end of the hood between its sides and from its open face inclinedly in one direction, the outer members of the series being curved, and a similar series of plates extending from the opposite 30 end of the hood like said first-named series but with its members inclining in the opposite direction, said plates forming between them inclined air-passages and between their inner ends and the hood an air-passage lengthwise 35 through the device, for the purpose set forth.

4. A car-ventilator comprising, in combination, a hood with open ends and face, a series of plates extending from one end of the hood between its sides and from its open face inclinedly in one direction toward the crown, 40 a similar series of plates extending from the opposite end of the hood like said first-named series, but with its members inclining in the opposite direction, said plates forming between them inclined air-passages and 45 between their inner ends and the hood an air-passage lengthwise through the device, and air-current deflecting-plates in the opposite ends of said passage, for the purpose set forth.

5. A car-ventilator comprising, in combination, a hood with open ends and face, a series of plates extending from one end of the hood between its sides and from its open face inclinedly in one direction toward the crown, 50 said plates increasing in length in the inward direction of the series, a similar series of plates extending from the opposite end of the hood like said first-named series but with its members inclining in the opposite direction, said plates forming between them inclined air-passages, and between their inner ends and the hood an air-passage through the device, and air-current deflecting-plates inclining toward the crown in the opposite ends 55 of said passage, for the purpose set forth.

GEORGE C. BREIDERT.
